UNITED STATES PATENT OFFICE.

EDWIN M. WHEELOCK, OF WINONA, MINNESOTA.

TRACTION-ENGINE.

1,052,867.

Specification of Letters Patent. Patented Feb. 11, 1913.

Application filed June 9, 1911. Serial No. 632,274.

To all whom it may concern:

Be it known that I, EDWIN M. WHEELOCK, a citizen of the United States, residing at Minneapolis, in the county of Hennepin 5 and State of Minnesota, have invented certain new and useful Improvements in Traction-Engines, of which the following is a specification.

My invention relates to a traction engine, 10 in which the prime mover comprises a motor of the explosive type, especially designed for the development of a relatively high power, to be used in pulling gang plows and other agricultural machinery and for other 15 purposes where a high power and reliable gas tractor is desired.

It is a principal object of my invention to provide an engine of this type which shall develop the necessary power and have 20 the capacity for enduring the hard service to which it will necessarily be subjected and at the same time be relatively light and have the parts thereof conveniently arranged and 25 easily accessible for the purpose of care and repair.

An especial object of my invention is to provide a frame for a traction engine which shall be wide enough to receive and support a four cylinder, or other multiple cylinder, 30 explosive engine of the horizontal opposed cylinder type, said frame being so trussed and stiffened by special cross-members as to be rigid and free from warping, however rough the ground on which the engine is operating, and at the same time requiring a 35 relatively small weight of material.

A further object of my invention is to form directly as a part of such framework a housing for the shaft upon which the traction 40 wheels are mounted.

A further object of my invention is to provide a divided axle for the front or steering wheels of the engine having a central part upon which the frame of the engine is 45 supported at a single point, said central axle being free to oscillate in a vertical plane about said point of support but being restrained from movement in a horizontal plane, excepting in a very slight degree by 50 special means to be hereinafter more fully described.

A further object of my invention is to provide a cab on said framework having novel structural features and an arrangement of said cab and the operating parts of 55 the machine including the oil receptacle on

said framework such as will produce a compact easily accessible strong and durable machine.

Other objects and advantages of my invention will appear in the detail description thereof and are particularly pointed out in the claims.

In the drawings illustrating the application of my invention in one form,—Figure 60 1 is a plan view with the casing and cab removed. Fig. 2 is a sectional elevation taken on a line substantially through the center of the machine. Fig. 3 is a side elevation with the casing and cab removed with some portions broken away to show certain features. Fig. 4 is a rear elevation. Fig. 5 is a rear 65 sectional elevation taken in part through the frame housing for the traction wheel axle. Fig. 6 is a sectional elevation taken on line 70 9—9 of Fig. 3 and viewed toward the front of the machine. Fig. 7 is a plan view of the cross-web casting used in stiffening the frame of the traction engine. Fig. 8 is a 75 transverse section of the same.

The frame of my engine comprises an upper and lower deck, the upper deck providing the means of supporting the frame upon the wheels and the means of supporting the various operative parts of the engine 80 85 while the lower deck is so constructed and braced to the upper deck as to give very great rigidity and at the same time provide the drawbar attachment of the engine to the load to be drawn thereby. The frame of 90 the upper deck, as clearly shown in Fig. 1, comprises main longitudinal channel beams 20 and 21 extending from front to rear of the machine and secured together by transverse channel beams 22 and 23 at the front 95 of the machine, transverse channel beam 24 toward the rear of the machine and transverse channel beam 25 at the extreme rear of the upper deck. These frame pieces are securely riveted together, the transverse 100 channel beam 25 being secured to the longitudinal channel beams 20 and 21 by a bevel joint, as indicated at 26 in Fig. 1, angle plates 27 being set into the respective channels of the beams and riveted to the webs 105 of said beams, as shown in Fig. 4. Bolted to the longitudinal beams 20 and 21 near the rear of the upper deck is a heavy transverse casting 28 the body portion of which is semi-tubular, a cross section thereof being 110 U-shaped, as clearly shown in Fig. 2. The casting 28 is provided at either side with

upstanding webs 29 having flanges 30 transverse thereto, said flanges being secured by bolts 31 to the web of the channel members 20 and 21. The casting 28 is additionally provided near the ends thereof with top lugs 32 which, together with bolts 33, provides means for additionally securing the casting 28 to the lower flanges of the channel beams 20 and 21. Corresponding lugs 34 are also provided near the lower edges of the casting 28 for a purpose to be later described. The casting 28 in addition to being a part of the frame of the machine adding very materially in strengthening and stiffening the same transversely has the special function of providing a housing and bearing for the shaft 35 of the traction wheels 36.

The lower deck of the framework comprises two longitudinal angle beams 37 and 38, each bent, as shown at 39 so as to have an ascending portion 40 which is bolted to the channel beam 20 or 21 at 41, the main portion of the angle beams 37, 38 extending parallel with and below the channel beams 20 and 21 and to a point somewhat to the rear thereof to bring the end of the lower deck back of the rearward peripheral extent of the traction wheels. The angle beams 37 and 38 are transversely connected forward of the center thereof by an angle bar 42 and have bolted to the rear end thereof of an angle bar 43, which extends at either side of the angle beams 37 and 38 practically to the outer limits of the traction wheels. The main portions of the members 37 and 38 are secured in parallel relation to the channel beams 20 and 21 by means of vertical angle beams 44 and 45 bolted or riveted to both of said sets of longitudinal frame members. Just above the point 39 where the members 37 and 38 are bent upwardly a two-armed casting 46 is bolted to the upwardly extending portion 40 of each of the members 37 and 38, the vertical arms 47 and the oblique arms 48 of said castings being bolted to the lower flange of the channel members 20 and 21.

To provide the necessary stiffness to the frame to meet the racking strain to which my engine will be subjected in the work of going over the rough ground in plowing or other farm operations I have provided the frame member illustrated in detail in Figs. 7 and 8. This member is a casting having at each end thereof a triangular web 49 connected by a transverse web 50. The triangular webs 49 are each provided with flanges 51, 52 and 53, respectively, the upper flanges 52 being bolted to the flanges of the channel beams 20 and 21, the lower flanges 51 being similarly bolted to the ascending portions 40 of the angle beams 37 and 38, as clearly shown in Fig. 3. The web 50 is provided 65 with a forwardly extending flange 54 and a

short rearwardly extending flange 55. Upon the flange 54 is secured a transverse beam 56 which is bolted at one end to the channel beam 20 but does not extend across the upper deck of the framework to the channel beam 21, being secured at its inner end to a longitudinal channel beam 57. The channel beam 57 extends across from the flange 54 of the web 50 to the transverse beam 23. The rectangular frame system composed of the longitudinal beams 20 and 57 and the transverse beams 23 and 56 provides the means of support for the four-cylinder gasoline engine designated generally by the character 58, said engine being an opposed cylinder horizontally mounted type. The use of the web casting 50 not only connects the upper and lower deck of the frame together so as to give an unusual degree of stiffness thereto, but permits a disposition of the engine such that while the same may be carried relatively well down in the frame a direct gear drive is permitted with frame clearance for the gearing, as shown in Figs. 1 and 2. The upper and lower decks at the rear portion thereof are additionally braced transversely by means of a pair of stayrods 59 and 60 each bolted to an upper and lower longitudinal member in front of the casting 28 and extending diagonally between said members and being bolted together at 61. A similar pair of cross stayrods 62 and 63 are similarly secured to the framework at the rear end thereof while oblique braces 64 extend from the top of the uprights 44 to the rearwardly extended portions of the angle bars 37 and 38. A reach-like channel iron 65 is secured to the transverse members 42 and 43 and to additional transverse members 66 and 67 suspended from the framework, the member 66 being directly suspended from the portion 40 of the bars 37 and 38 by hangers 68 while the members 67 is supported from the channel beams 20 and 21 by means of hangers 69 and cross braces 70 and 71, as shown most clearly in Figs. 2 and 3. The reach 65 is further united with the lower deck of the frame by means of horizontal cross braces 72 and 73 bolted at the point of crossing to the reach 65 and at their forward ends to members 37 and 38, being again bolted at 74 and 75 to members 38 and 37, respectively, and extending beyond said members to the transverse drawbar 43 to which the crossbars are bolted at 76 and 77, respectively.

As shown in Figs. 1, 2 and 3, the transverse drawbar 43 is provided with means for attachment to the object to be pulled by the traction engine. A central member forming such means of attachment consists of a U-shaped member 78 having hooks 79 and 80 extending over the edge of the transverse drawbar 43 on each side of the reach 65 and riveted to said drawbar at 81 and 82, re-

spectively. In pulling plows and other agricultural machinery it is usually desirable to attach the same to the traction engine at a point to one side or the other of the center of draft. This point may need to be varied in connection with different forms of the machines, for which reason I have devised the adjustable clevis connections 82.

As above indicated, the transverse casting 10 28 provides means for securing the traction wheels to the frame of the machine through the shaft 35. As shown in Fig. 2, the member 28 is open at the bottom and at either end is provided with sets of lugs 34 15 adapted to coöperate with similar lugs 88 on plates 89, said plates being adapted to secure in position within the member 28 bushing blocks 90 forming bearings for the shaft 35. These bushings may be made in 20 two sections, the upper section or real bearing block being semi-cylindrical so that when such a member becomes worn it may be readily slipped out and a new slip bushing placed in bearing position in its stead. 25 The shaft 35 extends a distance at either side of the frame member 28 sufficient to provide for mounting thereon of the traction wheel hubs 91, said hubs having thereon spiders 92 and 93 forming means of attachment for the wheel spokes 94 and also 30 an additional spider 95 to which the main driving gears 96 are secured. The spokes 94 secure the wheel rim 97 in position in a manner well known. Said spokes are rectangular in shape and are provided with a 35 double turnbuckle 98 by which the wheel rim is centered with respect to the shaft 35 and the spokes 94 properly tightened. The wheel rim is reinforced at the edges there- 40 of by rings 99 of angle iron. The gear 96 operates in a closed gear casing 100 of the type shown and described in Patent Number 986,614. One of the hubs 91 is keyed to rotate with the shaft 35, as shown at 101, in 45 Fig. 5, the other wheel 36 being free to rotate on said shaft to permit the necessary differential speeds when the engine is being driven around curves.

The front end of the engine is sustained 50 by steering wheels 102 mounted upon short axles pivoted on pins 105 positioned between the bifurcated ends 106 of the front axle 107. The frame of the machine is supported directly upon the axle 107 at the center 55 thereof by means of a two-armed casting 109 having a bifurcated lower end 110 straddling the axle 107, as shown in section in Fig. 2. Each of the arms of member 109 is provided with a central web 111 having a 60 vertical flange 112 bolted directly to the web of the channel beams 20 and 21, the said arms also having a double flange structure 113 extending beneath the channel beams 20 and 21 and by means of which the 65 arms of the member 109 are bolted to the

lower flanges of said channel beams, as shown at 114 in Fig. 6.

The steering rod 115 is operated by means of a belt 132 having a length of sprocket chain 133 extending about a sprocket wheel 134 on the rear end of the rod 115. A similar length of sprocket chain 135 extends about a sprocket wheel 136 on a horizontal shaft 137 mounted in bearings within the cab of the engine, said shaft 137 being provided 70 with a hand wheel 138 by which the same is rotated to correspondingly rotate the rod 115 for the purpose of steering the machine. The intermediate connections of the belt 132 comprise a turnbuckle 139 for tightening the belt to render certain and accurate the operation thereof. The vertical bearing portions 104 of the steering axles are provided with rearwardly and downwardly extended arms 140, the two arms 140 of said steering axles being connected so that the same will necessarily move in unison by means of the cross link 141.

The motor 58 is a four cylinder gas engine of well known type and operates a central crank shaft 149 working in a closed crank box 150 which box has a removable lid 151. The crank shaft 149 is provided with a hand cranking device 152 of common construction. Loose upon the crank shaft 149 is a sleeve carrying a pulley 153 and driving gear 154, said sleeve being adapted to be clutched to the shaft 149 by means of a clutch 155 operated by an angle lever 156 horizontally pivoted to the upper platform 90 of the frame, said angle lever being operated by hand lever 157 pivoted to the frame at 158 and pivotally connected by means of a link 159 to lever 160 pivoted to the frame and having a bifurcated end 161 embracing 95 the other arm 162 of the angle lever 156. 100

Upon a short shaft 163 journaled upon frame members 21 and 57 a gear 164 is provided which meshes with a gear 165 fast on a square shaft 166 journaled upon frame 110 members 20 and 21. Mounted to slide on the shaft 166 is a sleeve 167 having thereon different sized pinions 168, 169, and 170 adapted to mesh with gears 171, 172 and 173 fast on the driving shaft 174 journaled in boxes attached to the lower sides of the longitudinal frame members 20 and 21, said shaft having at the ends thereof gears 175 adapted to mesh with the gears 96 on the hubs 91 of the traction wheel members. The sleeve 167 is adapted to be moved along the square shaft 166 to bring the different pinions thereon into mesh with the different gears on the shaft 174 for driving the traction engine at different 115 speeds by means of an angle lever 176 having a fork connected with said sleeve, said angle lever being pivoted at 177 to the transverse frame member 24 and being connected by a link 178 pivotally con- 120 125 130

nected at 179 to change speed lever 180. Pivoted in a bracket 181 secured to the cross web 50 is a rocking arm 182 to which is journaled an idler pinion 183 adapted, when thrown into position, to mesh at the same time with gear 169 on sleeve 167 and gear 171 on shaft 174 whereby the engine may be driven in reverse direction, the reversing gear 183 being swung in and out of position 5 by means of a lever 184 similar to lever 180 and directly connected with arm 182 by a link pivoted to lever 184 at 185. As shown in Fig. 1, shaft 174 is provided with a brake drum 186 with which coöperates a brake 10 shoe, not shown, which brake shoe is controlled by lever 187 operating winding drum 188 upon which is the chain 189 for actuating the brake drum.

As previously stated, the motor is of ordinary construction being provided with the usual parts necessary for the operation of a four cylinder gas engine, the muffler 190 being shown in Fig. 3 and the radiator 191 in Figs. 1, 2, 3 and 6, said radiator being secured between the channel beams 20 and 21. To force a current of air through the radiator for cooling purposes a fan 192 is mounted on a longitudinal shaft 193 held in bearings 194 and 195 on the frame pieces 22 and 23. The fan is driven by a belt 196 passing around a pulley 197 on the shaft 193 and around a larger pulley 198 on a longitudinal shaft 199, one end of said shaft being mounted to rotate in hangers 200 and 201 20 depending from the transverse frame members 22 and 23, the other end of said shaft being mounted in a boxing 202 carried by a bracket 203 bolted to the web 50, as shown in Fig. 2. The end of the shaft within the 25 said box is provided with a bevel gear 204 meshing with a bevel gear 205 on a shaft 206 having thereon a pinion 207 meshing with the gear 164. By means of these connections the fan 192 is rotated at a high rate 30 of speed to produce the air current desired 35 for the necessary cooling action.

A frame casing 208, as shown in section in Fig. 2, incloses the upper portion of all the operative parts of the machine excepting 40 part of the muffler, said casing being held in position by arch members 209 and extending rearwardly to the front wall of the cab 210, which cab, as clearly shown in Figs. 2 and 5, is mounted directly upon the upper frame 45 members 20 and 21. The cab is provided with a front window 211 and with offset portions at the sides 212 and 213, said offset portions having windows 214 and 215, respectively, in the front thereof and side 50 windows 216. The cab is provided with an upholstered seat 217 in one corner thereof in convenient proximity to the steering wheel 138 and the various operative levers. Steps 218 are provided extending from the 55 transverse drawbar 43 up to the floor 219

of the cab upon the top of the upper deck frame. Secured between the transverse channel beam 24 and the web 50 is a lower gear casing 220 having a depressed portion 221 at the bottom thereof immediately beneath the shaft 174 and the gears thereon, which casing and more especially the said depressed portion are adapted to contain oil so that the gearing will be continuously oiled by running freely in a bath thereof while absolutely protected from intrusion of sand or dirt by the casings 220 and 208. 70

A space of triangular cross section above the gearing and extending back within the cab is utilized by placing therein a gasolene tank 222, which puts the gasolene in convenient proximity to the engine and at the same time sufficiently removed therefrom to do away with any danger of heating, the gasolene being conveyed to the cylinders of the engine through feed and carbureter mechanism of well known construction, which need not herein be described. The flat table-like portion 223 within the cab above the gasolene tank may, if desired, be utilized as a place of storage for tools or even for additional gasolene, since the lookout windows 214 and 215 in the offset portions of the cab 212 and 213 will permit the operator to obtain steering view of the road 95 or work ahead even if the front window 211 be somewhat obstructed.

The boxes 90 forming the bearings for the shaft 35 of the traction wheels are oiled by means of oil passages 224, similar passages 100 225 providing means of injecting oil within the main gear casing 220, while an especial oil case 226 on the platform 223, through tubular connections not shown, provides means of oiling other operative portions of the machine.

The relation of the different parts of my machine one to the other and the mode of operation thereof have been very fully given in connection with the detailed description of such parts. The main features of novelty comprise the distinctive and special frame organization, giving an exceedingly high degree of rigidity with a relatively light weight of material, and the combination of the operative parts of the machine with the characteristic features of such framework to produce a traction engine simple, compact, relatively light, and yet strong and durable in construction. The introduction of the semi-tubular transverse frame casting 28, providing within itself the means for housing the bearings of the shaft of the traction wheels, and also the wide web casting 50, secured to both the upper and lower decks of the frame of the machine, have the effect of absolutely preventing any warping or twisting whatever of said frame as the engine is rocked from one side to another when the traction wheels are being driven.

over uneven ground. This rigidity of the frame together with absolute freedom of oscillation of the steering axle in a vertical plane has the effect of retaining all of the operative parts in exact adjustment and most efficient working condition no matter how uneven or rough the ground upon which the traction engine must operate.

I claim:

1. A traction engine comprising a frame having an upper deck formed of longitudinal and transverse members rigidly secured together, one of said transverse members being a semi-tubular casting open at the bottom, bearing blocks within said casting and removable through said bottom opening, a shaft in said bearings, traction wheels on the shaft, and means supported by the frame to drive the traction wheels. 70
2. A traction engine comprising a frame formed of transverse and longitudinal channel beams rigidly secured together, and an additional transverse frame member consisting of a semi-tubular casting having webs and flanges by which said casting is secured to both the webs and the flanges of the longitudinal channel beams so as to be positioned directly beneath the same, the ends of said casting extending outside of said longitudinal beams, a shaft within said casting held in bearings positioned directly beneath said longitudinal beams and removable through the open side of said casting, traction wheels on the shaft, and means supported by the frame to drive the wheels. 80
3. A traction engine comprising a frame having an upper supporting deck and a lower draft deck each formed of longitudinal and transverse members rigidly secured together and the two decks being trussed and cross-braced to form a substantially integral structure, and a casting formed with portions extended in the vertical planes and bolted to the longitudinal members of both decks and an integral wide web extending transversely of the frame between the two decks. 85
4. A traction engine comprising a frame having two parallel decks each formed of longitudinal and transverse members rigidly secured together and the two decks being trussed and cross-braced to form a substantially integral structure, and a casting bolted to the longitudinal members of both decks having a wide web extending transversely of the frame between the two decks, said web being obliquely disposed and formed with a horizontal flange on the upper edge thereof, and a supplemental frame having a transverse member extending only partly across the upper deck supported upon said horizontal flange. 95
5. A traction engine comprising a frame having two parallel decks each formed of longitudinal and transverse members rig- 100
10. idly secured together and the two decks being trussed and cross-braced to form a substantially integral structure, and a casting bolted to the longitudinal members of both decks having a wide web extending transversely of the frame between the two decks, said web being obliquely disposed and formed with a horizontal flange on the upper edge thereof, a supplemental frame having a transverse member extending only partly across the upper deck supported upon said horizontal flange, a motor mounted within the supplemental frame, gearing mounted in the main frame of the upper deck including a driving shaft extending outside of the longitudinal members thereof at both ends and intermediate gearing mounted between the supplemental frame and one of said longitudinal members for connecting the motor with the first named gearing. 105
6. A traction engine comprising a frame having two parallel decks each formed of longitudinal and transverse members rigidly secured together and the two decks being trussed and cross-braced to form a substantially integral structure, the longitudinal members of the lower deck being bent upwardly and attached to the corresponding members of the upper deck near the middle thereof, and a casting bolted to said upwardly extending portions and to the longitudinal members of the upper deck having a wide web extending transversely of the frame between the two decks. 110
7. A traction engine comprising a frame having two parallel decks each formed of longitudinal and transverse members rigidly secured together and the two decks being trussed and cross-braced to form a substantially integral structure, the longitudinal members of the lower deck being bent upwardly and attached to the corresponding members of the upper deck near the middle thereof, and a casting provided with triangular vertical flanged webs, the flanges thereof being bolted to the said upwardly extending portions and to the longitudinal members of the upper deck, and a wide web extending between said triangular webs and transversely of the machine between the two decks. 115
8. A traction engine comprising a frame having two parallel decks each formed of longitudinal and transverse members rig- 120

thereon for attaching the engine to the object to be pulled at one or more independent points along said transverse member.

9. A traction engine comprising a frame having two parallel decks each formed of longitudinal and transverse members rigidly secured together and the two decks being trussed and cross-braced to form a substantially integral structure, the upper deck 5 including supporting means for the operative parts of the machine, and the lower deck including a transverse angle iron member extending outwardly to the rear of the traction wheels, and means for attaching the 10 engine to its load on and adjustable along 15 said transverse member.

10. A traction engine comprising a frame having two parallel decks each formed of longitudinal and transverse members rigidly secured together and the two decks being trussed and crossbraced to form a substantially integral structure, and a casting bolted 20 to the longitudinal members of both decks having a wide web extending transversely of the frame between the two decks, a supplemental frame within and of less width than said upper deck partially supported by said wide web, a multiple opposed-cylinder explosive engine horizontally supported within said supplemental frame having the crank-shaft thereof journaled in the longitudinal frame members of both the main frame and the supplemental frame of the upper deck, gearing mounted in the main frame of the upper deck including a driving shaft extending outside of the longitudinal members thereof at both ends, and an intermediate gear mounted between the supplemental frame and one of said longitudinal members for connecting said engine shaft with said gearing.

11. A traction engine comprising a frame having an upper supporting deck and a lower draft deck each formed of longitudinal and transverse members rigidly secured

together and the two decks being trussed and cross-braced in both vertical and horizontal planes to form a substantially integral structure, a multiple opposed cylinder explosive engine supported by and horizontally disposed within the upper deck, direct spur-gear transmission gearing, operatively connected with said engine, supported upon said upper deck and positioned above and below the plane of said deck, a 50 gasoline tank supported directly upon the upper deck and forming a part of a casing inclosing said transmission gearing, and a draw bar having direct connection with the lower deck. 60

12. A traction engine having two decks each formed of longitudinal and transverse members secured together to form a substantially integral structure, one of said transverse members being a casting bolted 65 to the longitudinal members of both decks and having a wide web extending transversely of the frame between the two decks, said web being formed with a horizontal flange on the upper edge thereof, a supplemental frame having a transverse member extending only partly across the upper deck supported upon said horizontal flange, a multiple opposed cylinder engine horizontally supported in said supplemental frame, 70 and transmission gearing including a train of direct drive spur gears transversely journaled upon the longitudinal members of the upper deck and operatively meshing through from front to rear of said web in 75 the clearance space afforded between the supplemental frame and the adjacent longitudinal member of the upper deck. 80

In testimony whereof I affix my signature in presence of two witnesses.

EDWIN M. WHEELOCK.
